UNITED STATES PATENT OFFICE

2,029,890

CONDENSER FOR REFRIGERATING MACHINES

Delbert F. Newman, Schenectady, N. Y., assignor to General Electric Company, a corporation of New York

Application December 1, 1934, Serial No. 755,559

10 Claims. (Cl. 257—36)

My invention relates to air cooled condensers of the type arranged to surround a casing of a refrigerating machine and carried on a heat conducting support extending about the casing.

5 An object of my invention is to provide an air cooled condenser of the type referred to above for refrigerating machines which provides a relatively large heat dissipating surface within a relatively small space about the casing and which 10 is provided with smooth exterior surfaces which are easily cleaned and attractive in appearance.

A further object of my invention is to provide an air cooled condenser of the type referred to above for refrigerating machines, which is rugged 15 in construction and economical in manufacture.

15 Further objects and advantages of my invention will become apparent as the following description proceeds and the features of novelty which characterize my invention will be pointed 20 out with particularity in the claims annexed to and forming a part of this specification.

25 For a better understanding of my invention, reference may be had to the accompanying drawing in which Fig. 1 is a front elevation of a refrigerating machine adapted to cool a refrigerator cabinet or the like, the refrigerating machine having an air cooled condenser embodying my invention; Fig. 2 is a perspective view, partly in section, of the air cooled condenser and casing 30 shown in Fig. 1, and Fig. 3 is a fragmentary sectional view of the upper portion of the air cooled condenser shown in Fig. 2.

35 Referring to the drawing, in Fig. 1 I have shown an hermetically sealed casing 10 containing a motor driven compressor unit, which supplies compressed refrigerant to an air cooled condenser 11 embodying my invention. The compressed refrigerant is liquefied in the condenser 11 and flows through a conduit 12 to a flow-controlling 40 float valve 13 from which it passes through the liquid line 14 to a flooded type evaporator 15. The evaporator 15 is supported on the lower side of an upper removable wall 16 of a refrigerator cabinet. The liquid refrigerant passing to evaporator 45 15 is vaporized by the absorption of heat from the interior of the refrigerator cabinet in which the evaporator 15 is located, the vaporized refrigerant being collected in headers 17 of the evaporator 15. The vaporized refrigerant collected in the headers 17 above the level of the liquid refrigerant therein is drawn off through the suction line 18 by the motor driven compressor in the casing 10.

50 The air cooled condenser 11, which embodies my invention, includes an imperforate cylindrical

member made of sheets of metal 19 and 20, as best shown in Fig. 2. Complementary sinuous indentations 19^a and 20^a are formed in the sheets 19 and 20, respectively, the sheets 19 and 20 are then secured together in face engagement by 5 welding or otherwise securing them together along their edges and between the indentations formed therein. The welding may be in the form of a line weld or a series of closely spaced spot welds. The sheets are then bent into the form of 10 a cylinder and their ends secured together by welding or otherwise, along a seam 22. When so assembled with the indentations in one sheet registering with those in the other, the sheets 19 and 20 define a sinuous refrigerant passage 21 between 15 their opposed faces which extends substantially about the cylindrical member.

A zig-zag annulus of fins 23, made of good heat conducting material, extends about the hermetically sealed casing 10, a series of slots 25 being 20 formed in the outer edge of the annulus 23. A heat dissipating refrigerant conduit 24 is provided in the form of a helix which surrounds the casing 10 and is supported in the slots 25 in the annulus 23.

25 In assembling the condenser construction described the refrigerant conduit 24 is wound about the annulus 23 in the slots 25 formed therein. The inside diameter of the imperforate cylindrical member made up of sheets 19 and 20 is made 30 somewhat smaller than the outside diameter of the annulus 23 so that the cylindrical member may be force-fitted on the annulus. The inside diameter of the annulus 23 is preferably arranged to be slightly smaller than the outside diameter 35 of the casing 10 when the cylindrical member is in position on the annulus. The assembled cylindrical member and annulus may then be force-fitted on the casing 10. Good heat conducting contact is thus provided between the casing 10 and 40 the annulus 23 and between the annulus 23 and the cylindrical member made up of sheets 19 and 20.

45 Gaseous refrigerant compressed by the motor driven compressor unit contained in the casing 10 enters the refrigerant conduit 24 at inlet connection 26, passes through the heat dissipating refrigerant conduit 24 and enters the refrigerant passage 21 at 27. After circulating 50 through the refrigerant passage 21 the condensed refrigerant leaves the air cooled condenser 11 through the liquid line 12. In the operation of the refrigerating machine described, heat is dissipated from the casing 10, the annulus 23, and the cylindrical member made up of sheets 19 and 55

20 by air circulating upwardly between the casing and the cylindrical member, the air being circulated by natural draft.

In this construction a large amount of heat 5 may be readily dissipated from the casing 10 not only to the surrounding air, but also through the annulus 23 to the air circulating over the surface thereof. Also a large amount of heat may be dissipated from the refrigerant as it passes in 10 series through the conduit 24 and the passage 21, the heat passing through the walls of the conduit and passage to the circulating air. It will be noted that the annulus 23 is also in good heat 15 conducting contact with the refrigerant conduit 24 and refrigerant passage 21, and as a result heat is transferred from the walls of the conduit and passage to the annulus 23 and then to the surrounding air. The slots 25 in the annulus 23, in which the refrigerant conduit 24 is supported, 20 are made deep enough so that the conduit 24 is supported in a portion of the annulus 23 which is at a sufficiently low temperature to cool the conduit. As best shown in Fig. 3 the refrigerant passage 21 is positioned adjacent the projecting 25 portions 28 of annulus 23, so that heat is conducted from the refrigerant in passage 21 to the radiating surfaces of annulus 23 through the minimum thickness of metal. By positioning the various elements as described, the heat dissipating 30 annulus 23 can be most effectively utilized.

While I have shown a particular embodiment of my invention in connection with a compression refrigerating machine, I do not desire my invention to be limited to the particular construction shown and described, and I intend in the appended claims to cover all modifications within the spirit and scope of my invention.

What I claim as new and desire to secure by Letters Patent of the United States, is:

40 1. A refrigerating machine having a casing, an air cooled condenser including a cylindrical member surrounding said casing in spaced relation thereto, a support of heat conducting material connecting said casing and said cylindrical member, and a heat-dissipating refrigerant conduit carried by said support intermediate said casing and said cylindrical member and extending about said casing.

50 2. A refrigerating machine having a casing, an air cooled condenser including a zig-zag annulus of heat conducting material surrounding said casing, an imperforate cylindrical member secured to the periphery of said annulus, and a heat-dissipating refrigerant conduit carried by 55 said annulus intermediate said casing and said cylindrical member and extending about said casing.

60 3. A refrigerating machine having a casing, an air cooled condenser including an imperforate cylindrical member surrounding said casing in spaced relation thereto, said cylindrical member including a plurality of sheets having juxtaposed faces and defining a sinuous refrigerant passage between their juxtaposed faces, a support of heat 65 conducting material connecting said casing and said cylindrical member, and a heat-dissipating refrigerant conduit connected to said refrigerant passage, said conduit being carried by said support intermediate said casing and said cylindrical member and extending about said casing.

70 4. A refrigerating machine having a casing, an air cooled condenser including a zig-zag annulus of heat conducting material surrounding said casing, an imperforate cylindrical member secured to the periphery of said annulus, said cylindrical member including a plurality of sheets having 75 juxtaposed faces and defining a sinuous refriger-

cylindrical member including a plurality of sheets having juxtaposed faces and defining a sinuous refrigerant passage between their juxtaposed faces, and a heat-dissipating refrigerant conduit connected to said refrigerant passage, said conduit being carried by said annulus intermediate said casing and said cylindrical member and extending about said casing.

5 5. A refrigerating machine having a casing, an air cooled condenser including a zig-zag annulus 10 of heat conducting material surrounding said casing and provided with a series of slots in the outwardly projecting portions of said annulus, an imperforate cylindrical member secured to the periphery of said annulus, said cylindrical 15 member including a plurality of sheets having juxtaposed faces and defining a sinuous refrigerant passage between their juxtaposed faces, said refrigerant passage being positioned adjacent the sections of said annulus intermediate said 20 slots, and a heat-dissipating refrigerant conduit connected to said refrigerant passage and supported in said slots.

6. A refrigerating machine having a casing, an air cooled condenser including an imperforate 25 cylindrical member surrounding said casing in spaced relation thereto, said cylindrical member including contacting metallic sheets joined together in face engagement, at least one of said sheets having a sinuous indentation formed there- 30 in cooperating with the other of said sheets to form a sinuous refrigerant passage extending about said cylindrical member, supporting means of heat conducting material connecting said casing and said cylindrical member, and a heat-dis- 35 sipating refrigerant conduit connected to said refrigerant passage, carried by said supporting means intermediate said casing and said cylindrical member and extending about said casing.

7. A refrigerating machine having a casing, an 40 air cooled condenser including a zig-zag annulus of heat conducting material surrounding said casing and provided with a series of slots in the outwardly projecting portions of said annulus, an imperforate cylindrical member secured to the periphery of said annulus, said cylindrical member including contacting metallic sheets joined together in face engagement, at least one of said sheets having a sinuous indentation formed there- 45 in cooperating with the other of said sheets to 50 form a sinuous refrigerant passage extending about said cylindrical member and lying adjacent the sections of said annulus intermediate said slots, and an extended heat-dissipating refrigerant conduit connected to said refrigerant pas- 55 sage and supported in said slots.

8. A refrigerating machine having a casing, an air cooled condenser including an imperforate cylindrical member surrounding said casing in spaced relation thereto, supporting means of heat 60 conducting material connecting said casing and said cylindrical member, and a heat-dissipating refrigerant conduit extending about said casing in heat-transfer relationship with said supporting means intermediate said casing and said cylindrical member and positioned on a portion of said supporting means which is at a sufficiently low temperature to cool said conduit.

9. A refrigerating machine having a casing, an air cooled condenser including a zig-zag annulus 70 of heat conducting material surrounding said casing, an imperforate cylindrical member secured to the periphery of said annulus, said cylindrical member including a plurality of sheets having juxtaposed faces and defining a sinuous refriger-

erant passage between their juxtaposed faces, and a heat dissipating refrigerant conduit connected to said refrigerant passage and supported by said annulus intermediate said casing and said cylindrical member and extending about said casing on a portion of said annulus at a sufficiently low temperature to cool said conduit.

5. 10. A refrigerating machine having a casing, an air cooled condenser including a zig-zag annulus of heat conducting material surrounding said casing and provided with a series of slots in the outwardly projecting portions of said annulus, an imperforate cylindrical member secured to the periphery of said annulus, said cy-

lindrical member including contacting metallic sheets joined together in face engagement, at least one of said sheets having a sinuous indentation found therein cooperating with the other of said sheets to form a sinuous refrigerant passage extending about said cylindrical member said refrigerant passage being positioned adjacent the sections of said annulus intermediate said slots, and a heat-dissipating refrigerant conduit connected to said refrigerant passage and supported in said slots at a portion of said annulus at a sufficiently low temperature to cool said conduit.

10. DELBERT F. NEWMAN.
